UNITED STATES PATENT OFFICE.

FREDERICK W. ACKERMAN, OF ROCHESTER, NEW YORK, ASSIGNOR TO YAWMAN & ERBE MANUFACTURING COMPANY, OF ROCHESTER, NEW YORK, A CORPORATION OF NEW YORK.

FILING-CABINET.

1,017,239.

Specification of Letters Patent.

Patented Feb. 13, 1912.

Application filed April 5, 1911. Serial No. 619,142.

To all whom it may concern:

Be it known that I, FREDERICK W. ACKERMAN, of Rochester, in the county of Monroe and State of New York, have invented certain new and useful Improvements in Filing-Cabinets; and I do hereby declare the following to be a full, clear, and exact description of the same, reference being had to the accompanying drawings, forming a part of the specification, and to the reference-numerals marked thereon.

The present invention relates to office furniture and more particularly to filing devices and it has for its object to provide a cabinet suitable for the proper filing of blue prints, drawings and other large sheets and having provision for the support of the contents when temporarily withdrawn for inspection.

20 The improvements are directed more particularly toward means for promoting convenience of access to the cabinet and for maintaining the parts firmly in the extended and folded positions respectively assumed 25 when the cabinet is opened for the examination of the contents or closed to preserve and protect them.

To these and other ends the invention consists in certain improvements and combination 30 of parts, all as will be hereinafter more fully described, the novel features being pointed out in the claims at the end of the specification.

In the drawings: Figure 1 is a side elevation 35 of a cabinet constructed in accordance with and illustrating one embodiment of my invention, the body thereof being shown in vertical section; Fig. 2 is a perspective view 40 of one of the hanging pockets in which the drawings or other articles are filed; Fig. 3 is a detail section of one of the abutments employed for preventing the sheets from slipping from the extension shelf; Fig. 4 is a central vertical section through the cabinet 45 when closed, taken on the line 4-4 of Fig. 7; Fig. 5 is a fragmentary vertical section taken on the line 5-5 of Fig. 7; Fig. 6 is a detail section, enlarged, of one of the latches employed for holding the front of the cabinet 50 in place; Fig. 7 is a transverse section taken substantially on the line 7-7 of Fig. 4, looking in the direction of the arrows; and Fig. 8 is a fragmentary section enlarged 55 illustrating the operation of parts shown in Fig. 1.

Similar reference numerals in the several figures indicate similar parts.

Referring more particularly to the drawings and the reference numerals marked thereon, 1 indicates a suitable box-like casing having a top or cover 2 hinged at 3 and a front 4. At each side of the casing is provided a ledge 5 formed in the present instance, by a cleat 6 secured on the interior against the side wall and upon these ledges loosely rest the opposite projecting ends 7 of a plurality of rods or bars 8 though one only is shown in the present instance in Fig. 4 in order not to hide other parts. Hung from these rods are a plurality of flat bags 9 in which are placed one or more of the drawings or other sheets 10 for which the cabinet is adapted, in accordance with the vertical system of filing. The front flap 11 of the bag is of greater or less length according to the position of an adjustable fastening device 12 revealing more or less of the contents when turned back, but it is normally held closed by a rod 13 at its edge having projecting ends 14, in the manner of the rods 8, that also rest on the ledges 5.

When it is desired to remove or inspect the contents of the bag, they may be separated slightly by sliding them along on the ledges and the one selected may be raised 85 slightly by means of its bar 8 whereat the flap 11 will fall back and partially disclose the interior. If desired however, the entire bag may be withdrawn for a closer examination of its contents and to conveniently support it during this operation, the arrangements about to be described are made.

Hinged at 15, at the forward edge of the bottom 16 of the cabinet is a supporting frame 17, the hinge being at the lower end thereof while at its upper end the frame is hinged at 18 to the upper end of the front 4. In the folded positions of the parts the latter holds the frame 17 in a vertical position against the ends of the cleats 6; and is itself held against outward movement by a flange 19 on the top or cover 2 as shown in Fig. 4, and also by locking projections 20 on the sides of the cabinet which coöperate with spring actuated latches 21 on the sides of the front. One of these spring latches is shown in detail in Fig. 6 to comprise a bracket 22 on which the latch is pivoted at 23 and normally held in engaging position by a leaf spring 24, engaging an arm 25 110

thereon, a cam face 26 insuring an automatic engagement of the latch when the front is moved into coöperation with the cabinet walls. To open the cabinet and extend the parts, the cover 2 is raised rendering accessible a preferably centrally arranged releasing lever 27 (Figs. 5 and 7) pivoted at 28 near the upper edge of the front 4. This lever has connected to it on opposite sides of its pivot 28 as at 29 and 30, pull rods 31 respectively connected with the arms of bell crank levers 32, one of which latter is provided at each side of the front 4. The other arms of the bell cranks are connected to pull rods 33 which in turn are connected to the respective latches 21. Thus it will be seen that by moving the lever 27 to the right in Fig. 7, both latches will be simultaneously released and, the cover 2 being raised, the front may be swung upwardly on its hinged connection 18 with the frame 17 to the position shown in Fig. 4, in which it constitutes an extension shelf for the display of the drawings. As the front assumes this extended position, the supporting frame 17 is allowed to tilt outwardly on its hinge 15 to a certain extent limited by a link 34 (Figs. 1 and 8) pivoted thereto at 35. This link is provided with a guiding slot 36 in which operates a headed pin or abutment 37 on the cleat 6 and it may be stated here that there is one mechanism such as that being described at each side of the cabinet but the description of one will suffice for both. When the frame is tilted outwardly to the limit of its movement, the abutment 37 is engaged by a locking shoulder 38 at the end of the slot 36 that normally prevents the frame from rocking backward again and holds it firmly in position. The link 34 at this time serves as a continuation of the ledge 5 permitting the bags 9 to be separated to a greater extent than usual so that the intermediate ones may be made freely accessible. I provide means, however, for automatically disengaging the locking shoulder 38 from the abutment 37 when the extension shelf 4 is lowered or folded against the frame 17 to close the front of the cabinet, to which end the link 34 is provided on the outer side of the frame 17 with a spring arm 39 and upon the depression of this arm as indicated in dotted line in Fig. 8 by the engagement of the front 4 with the frame in the initial movement of the closing operation, it tends to raise the link 34 so that as the two members 4 and 17 are further moved inwardly, the locking shoulder will ride over the abutment 37 and continue down the slot or guide 36 to the position shown in Fig. 4. The weight of the link 34 is relied upon, in the present instance, to insure the engagement of the locking shoulder 38 with the abutment.

I have described the manner in which the

rear or top edge of the member 4 is supported in extended position. The front edge is supported by a pair of legs 40 which are hinged at 41 (Fig. 4) at the lower edge of the front 4 and fold upwardly against it being normally accommodated between the front and the frame 17 for which purpose the latter is preferably recessed at 42 while the ends of the legs are correspondingly recessed at 43. In this way, the legs are made to lie in the same plane with the frame 17 and to therefore occupy very little room. Each leg is fitted with a pair of springs 44 one end of each of which is connected to the leg at 45 and to the member 4 at 46 in such a manner that when the leg is swung from the folded position of Fig. 7 to the extended position of Fig. 1, or the reverse, the spring will pass from one side to the other of the axis 41 on which the leg hinges, the result being that the springs have a tendency to retain the legs in either position after they have been rotated to that position, as will be understood.

In Fig. 1 is illustrated the manner in which the bags 9 may be displayed upon the front 4 when the latter is in extended position. As it is, for convenience, inclined downwardly toward its front or bottom edge, the bag or the drawings and sheets it contains are liable to slide off, so to prevent this, I provide, in this region, one or more, preferably two, abutments 47 shown in Fig. 3 which normally lie below the upper surface of the shelf but are automatically projected therefrom when the shelf is extended and the leg 40 dropped. In the present instance, these abutments are formed by pins operating in sockets 48 in the body of the front 4 and are normally held depressed by springs 49 acting against the flanged end 50 of the socket and a shoulder 51 on the enlarged inner end of the pin. A shoulder 52 at the outer end of the latter limits its inward movement so that normally it does not project noticeably from the cabinet, but when the front 4 is extended and the legs 40 are dropped, the arrangements of the abutments is such, that the inner projecting end of each pin 47 is engaged by the end face 53 of an adjacent leg and thrust outwardly, as shown in Fig. 3. As soon as the leg is folded the pins assume their normal positions.

With the improvements described, utility and convenience of the cabinet to the user are greatly increased, and when the shelf is extended for the inspection of the contents it forms a rigid and firm support, yet in folding but a few simple operations are required because of the automatic working of many of the parts.

I claim as my invention:

1. The combination with a cabinet, a supporting member connected thereto for relative movement, and a front foldable against the supporting member and adapted to be

extended to form a shelf, of a sliding connection between the supporting member and cabinet comprising a link on one part provided with a guide terminating in a locking shoulder and an abutment on the other co-operating with the guide and shoulder, and means operating on one member tending to disconnect the locking shoulder from the abutment, said means being actuated by the front when moved to its folded position against the supporting member.

2. The combination with a cabinet, a supporting frame hinged thereto at its lower end to tilt outwardly and a front hinged to the upper end of the supporting frame to fold against the same or assume an extended position in which it constitutes a shelf, of a link pivoted to the supporting frame and provided with a guide having a locking shoulder, an abutment on the cabinet co-operating with the guide and engaging with the locking shoulder when the frame is tilted and a spring arm on the link operating, when compressed, to throw the shoulder and abutment out of engagement, said arm being actuated by the front when folded against the supporting frame.

3. The combination with a cabinet having a front adapted to be extended therefrom to constitute a shelf, of a leg hinged to the shelf to fold against the same, or to be extended to a supporting position and an abutment at

one side of the front normally lying below the surface thereof but automatically actuated to project above such surface by the action of the leg when the latter is extended.

4. The combination with a cabinet having a front adapted to be extended therefrom to constitute a shelf, of a leg hinged to the shelf to fold against the same, or to be extended to a supporting position and an abutment at one side of the front comprising a pin arranged in the body of the front, and a spring having a normal tendency to hold the pin below the outer surface thereof, said pin being actuated by the leg when the latter is extended, to project outwardly from the surface of the shelf.

5. The combination with a cabinet having a hinged front adapted to be extended to form a shelf, of a locking projection at each side of the cabinet, a spring latch on each side of the front arranged to co-operate with the respective projections, a bell crank for each latch having one arm pivotally connected thereto, a pivoted releasing lever arranged centrally of the front and members connected to the other arm of each bell crank, respectively, and connected to the releasing lever on opposite sides of its pivot.
